DESIGN FOR A BEAM AND DIAL CASING FOR A WEIGHING SCALE

Henry Dreyfuss, New York, N. Y., assignor to
Fairbanks, Morse & Co., Chicago, Ill., a corpora-
tion of Illinois

Application June 22, 1944, Serial No. 114,150

Term of patent 14 years

(Cl. D52—10)

To all whom it may concern:

Be it known that I, Henry Dreyfuss, a citizen
of the United States, residing at New York city,
in the county of New York and State of New York,
have invented a new, original, and ornamental
Design for a Beam and Dial Casing for a Weigh-
ing Scale, of which the following is a specifica-
tion, reference being had to the accompanying
drawing, forming part thereof.

In the drawing, the figure is a front perspec-
tive view of a beam and dial casing for a weigh-
ing scale, showing my new design, the back and
side not shown being plain.

I claim:

The ornamental design for a beam and dial
casing for a weighing scale, as shown and de-
scribed.

HENRY DREYFUSS.
